United States Patent Office

Des. 217,790
Patented June 9, 1970

217,790

DESK TRAY

Frank A. Oddo, 8460½ Golden Ave.,
Lemon Grove, Calif. 92045

Filed Mar. 17, 1969, Ser. No. 16,281

Term of patent 3½ years

Int. Cl. D19—02

U.S. Cl. D74—9

FIG. 1

FIG. 2

FIG. 3

FIG. 1 is a side elevational view of a desk tray, showing my new design, the side opposite thereto being similar in appearance;

FIG. 2 is a front elevational view thereof; and

FIG. 3 is a top view thereof.

I claim:

The ornamental design for a desk tray, as shown and described.
